 Pittman LLP(57) **CLAIM**

The ornamental design for a bottle, as shown and described.

DESCRIPTION

FIG. 1 is a top perspective view of a bottle according to the present invention;

FIG. 2 is a front elevation view of the bottle;

FIG. 3 is a back elevation view of the bottle;

FIG. 4 is a right side view of the bottle shown in FIG. 2 and FIG. 3;

FIG. 5 is a left side view of the bottle shown in FIG. 2 and FIG. 3;

FIG. 6 is a top view of the bottle as shown in FIG. 2 and FIG. 3; and,

FIG. 7 is a bottom view of the bottle as shown in FIG. 2 and FIG. 3.

The broken lines illustrate portions of a bottle that form no part of the claimed design.
